UNITED STATES PATENT OFFICE.

WILLIAM FONTAINE JOHNSTON, OF RICHMOND, VIRGINIA.

SCYTHE-FASTENER.

1,365,833.

Specification of Letters Patent. Patented Jan. 18, 1921.

Application filed September 30, 1920. Serial No. 413,742.

To all whom it may concern:

Be it known that I, WILLIAM FONTAINE JOHNSTON, a citizen of the United States, and a resident of Richmond, in the county of 5 Chesterfield and State of Virginia, have invented certain new and useful Improvements in Scythe-Fasteners, of which the following is a specification.

My invention relates to fasteners for 10 curing scythes to snathes and the purpose of my invention is the provision of a fastener of that character which positively secures the scythes to the snathes and without subjecting the snathe to any pressure or stresses 15 whereby distortion or wear of the snathe is prevented so that the possibility of its becoming weakened and breaking is eliminated.

I will describe one form of scythe fastener embodying my invention, and will then 20 point out the novel features thereof in claims.

In the accompanying drawings:

Figure 1 is a view showing in front elevation a portion of a conventional form of snathe and scythe having applied thereto 25 one form of fastener embodying my invention.

Fig. 2 is a vertical sectional view taken on the line 2—2 of Fig. 1.

Fig. 3 is a transverse sectional view taken 30 on the line 3—3 of Fig. 2.

Referring specifically to the drawings, in which similar reference characters refer to similar parts, S designates a snathe to the flat side of which is secured a rectangular 35 strip or plate of metal B. In the present instance the plate B is secured to the snathe S by means of bolts 15 which extend through the plate at points adjacent its opposite ends so as to securely retain the plate upon the 40 snathe. Snugly embracing the snathe S is a yoke or bracket K which, as illustrated to advantage in Fig. 3, is substantially of the same general outline as the cross sectional contour of the snathe. As shown in Fig. 3, 45 the curved portion of the yoke K is designated at 16 and is provided intermediate its ends with an opening surrounded by a collar 16^a, the wall of the opening and the inner side of the collar being screw threaded to 50 receive a set screw R. The linear portion of the yoke K is designated at 17, and in the applied position of the yoke such linear portion is disposed in spaced parallel relation to the plate B, with the curved portion 16 55 embracing the curved portion of the snathe S.

As shown in Fig. 3, the set screw R extends through a suitable opening formed in the snathe S so that its inner end is disposed to abut the inner side of the plate B. As 60 shown in Figs. 1 and 2, the plate B is provided with a set of lugs L at a point above the yoke K, and with another set of lugs L' at a point below the yoke K. As shown in Fig. 1, the set of lugs L have their working 65 faces arranged in the form of an arc, while the contact faces of the set of lugs L' are all arranged in the same plane. These lugs L and L' are adapted to contact with the edges of a shank A of the scythe blade C to lock 70 the shank against lateral movement upon the plate B. The free end of the shank A is provided with the usual lip 18 which fits within a suitable recess formed in the plate.

In the application of the scythe shank to 75 the fastener, it is inserted between the plate B and the linear portion 17 of the yoke K with its opposite edges engaging the lugs L and L'. With the shank A in this position, and the inner end of the set screw R abutting the plate B, it will be clear that upon further inward movement of the set screw a 80 movement of the entire yoke in the opposite direction is effected thus drawing the linear portion 17 in the direction of the shank A so 85 as to securely grip the shank between the yoke and plate.

It is to be particularly noted that by virtue 90 of this arrangement and operation the snathe S is never subjected to the pressure of the set screw nor the gripping action of the bracket so that the possibility of the snathe becoming distorted, worn or broken is eliminated. I consider this an important object 95 of my invention because in all scythe fasteners with which I am familiar their construction is such that after repeated use the snathe becomes worn, distorted or broken thus necessitating the employment of a new snathe. It is to be further noted that as the 100 inner end of the set screw R normally abuts or engages the inner side of the plate B, that in clamping position, the set screw, because of its frictional engagement with the plate, is locked against accidental turning so that 105 the bracket is maintained in clamping position.

Although I have herein shown and described only one form of scythe fastener embodying my invention, it is to be understood 110 that various changes and modifications may be made herein without departing from the

spirit of the invention or the spirit and scope of the appended claims.

What I claim is:

1. A scythe fastener comprising a plate adapted to be secured to the flat side of a snathe, snathe shank engaging projections formed on the plate, a yoke adapted to embrace a snathe in such manner that a portion thereof is disposed in spaced relation to said plate to permit the insertion of a scythe shank between the plate and yoke, and a set screw threadedly mounted within the yoke adapted to extend through the snathe and to engage the inner side of the plate so that when fed inwardly the yoke will be moved

in the direction of the plate to clamp the scythe shank between the yoke and plate.

2. A scythe fastener comprising, a plate adapted to be secured to the flat side of a snathe, a yoke adapted to embrace the snathe and having a linear portion disposed in spaced relation to said plate, and means for moving said yoke and plate into clamping engagement with each other.

3. A scythe fastener comprising, a yoke, a plate extending through the yoke, and means carried by the yoke and engageable with the plate for forcing the two into clamping engagement with each other.

WILLIAM FONTAINE JOHNSTON.
